UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

TROLLEY-WIRE CLAMP.

1,390,369.

Specification of Letters Patent. Patented Sept. 13, 1921.

Application filed June 9, 1920. Serial No. 387,595.

To all whom it may concern:

Be it known that I, SAMUEL S. MATTHES, a citizen of the United States, residing at Mansfield, in the county of Richland and 5 State of Ohio, have invented certain new and useful Improvements in Trolley-Wire Clamps, of which the following is a specification.

My invention relates to a clamping device 10 for engaging and supporting a trolley wire or other conductor from an overhead support.

The invention has for its object a construction which will simultaneously grip a 15 conductor and the supporting hanger and the grip upon each will increase proportionately and such gripping effect is brought about by a single operation and at the same time the device is rotatably adjustable with 20 reference to the overhead supporting member so that it may be brought into proper alinement with the trolley wire or other conductor.

These objects and others which will be 25 obvious to one skilled in the art are brought about by the construction, relation and combination of elements fully described and set forth herein and shown in the drawing accompanying this specification.

30 In the drawing:—

Figure 1 shows a side elevation of my invention in full as installed upon a trolley wire and overhead hanger.

Fig. 2 shows an end elevation view of the 35 device in Fig. 1.

Fig. 3 is a sectional view of my invention when it is made to just engage an overhead support and loosely holding a trolley wire between the jaws and this view is taken on 40 line 3—3 of Fig. 1.

Fig. 4 is a sectional view of my invention on the line 3—3 of Fig. 1 and shows the relation of parts when the device has been 45 fully installed and is thoroughly gripping the trolley wire and the hanger support.

Fig. 5 is a section on the line 5—5 of 50 Fig. 3.

Fig. 6 is a section on the line 6—6 of Fig. 3.

55 Fig. 7 is a view of the supporting element of my device.

Fig. 8 is a bottom view of the supporting element shown in Fig. 7 and the dotted lines, representing one of the clamping

members, will be used later in describing the 55 method of assembling the parts.

Fig. 9 is a modification of engagement between parts later referred to.

In the preferred form of clamp embodying my invention, although there are many 60 modifications which can be made from this form and still be within the scope of my invention, I employ a pair of clamping jaws 1—1 provided at their lower end with proper means 2 for engaging a trolley wire 65 conductor. At the upper end of each jaw is a flange 3 and a recess 4, the flange and recess on each jaw being semi-circular but when the two jaws are placed side by side they approximate an entire circular flange 70 and recess. Near the upper end of the jaw members is a shoulder 5 which I have shown as having a beveled surface although this surface might be at other angles than that shown in the drawing. One modification of the shoulder 5 is shown in Fig. 9.

To support the device embodying my invention from an overhead hanger H, I use a supporting member 6 which is internally threaded to engage the stud of the overhead 80 hanger and at its lower end is provided with a flange extending inwardly indicated by 7, and forming a recess 8. The flange 7 is adapted to engage in the recess 4 of the jaws and the flange 3 is adapted to engage 85 in the recess 8 of the supporting member. The flange 7 is not entire but has an opening from the outside as indicated by the numeral 15 in Fig. 8. This opening 15 permits the assembling of the jaws and supporting member as will be readily understood by considering the dotted lines shown in Fig. 8 to represent the flange and recess 90 3 and 4 respectively of the jaw member and positioned as shown with respect to the supporting member 6. The jaw represented by the dotted line is to be moved toward the supporting member 6 and to register with the opening 15 and it will be seen that 95 the jaw will slip into the slot 15 and flange 3 will engage in the groove 8 and then by giving the jaw a half turn within the supporting member 6 the second jaw can be 100 operated the same as the first and assembled with the supporting member 6. This permits the supporting member and the jaws to be held together by means of the engaging flanges 3 and 7 and at the same time the

jaws rotate freely, relatively to the supporting member 6.

The upper portion of the supporting member 6 is made hexagonal or other shape as will be pointed out later.

Surrounding the supporting member 6 is a collar 9 provided at its upper exterior surface with the hexagonal construction as shown in Fig. 6 for the application of a wrench used in installing the device. The exterior upper surface of the collar is made hexagonal or other shape to correspond with the hexagonal or other shape on the supporting member 6 as shown in Fig. 6 in order to cause the supporting member and the collar to rotate in unison whenever the collar is rotated in either direction. The lower end of the collar is provided with a surface 10 which engages with the surface 20 on the shoulder 5 of the clamping jaw. In order to hold the parts together so as to prevent their disassembling, the upper portion of the supporting member 6 is grooved and a spring ring 11 positioned therein and this ring projects beyond the surface of the supporting member and engages with an internal shoulder on the collar as indicated in Fig. 3, thereby preventing the disassembling of the parts. The ring 11 is so located relatively to the stop shoulder on the collar as to permit the collar to move longitudinally or vertically (as shown in the drawing) of the supporting member and this relative movement is necessary in order that the device may be installed, at the same time the collar and supporting member are to rotate in unison.

The principle and operation of installing my invention as herein described consists first of securing the device to the stud of the overhead insulated hanger or support so that the supporting member will safely engage the stud of the overhead support as indicated in Fig. 3. The jaws are then rotated angularly relatively to the overhead support until they align with the trolley wire or other conductor 12. The conductor is then slipped between the jaws of the device and held in position while the collar 9 is rotated. The rotation of the collar in the right direction will cause the supporting member 6 to rotate and as the stud 13 on the hanger is fixed the supporting member will be drawn upwardly upon the stud 13 until the upper face 55 of the collar 9 engages the lower face 14 of the hanger.

As soon as the collar 9 engages the face of the hanger the upper movement of the collar will be arrested but if the rotation of the collar is continued, the clamping member 6 will continue to be drawn upwardly on the hanger stud 13 and with it the jaw members 1 will be raised until the shoulder 5 of the jaws contacts with the surface 10 of the collar. As soon as this condition takes place

a still further rotation of the collar and with it the supporting member will cause the jaws to be moved inwardly at their lower end, thereby gripping the trolley wire and as the grip on the trolley wire increases through continued rotation of the collar 9 the pressure between the collar 9 and the hanger will be increased simultaneously.

The upper end of the jaw members 1 will be prevented from moving inwardly under pressure of the collar on account of their contacting at the point 16 which becomes a pivotal point.

While I have illustrated and described the preferred construction embodying my invention, still I know that many modifications of the same may be made by those skilled in the art without departing from the scope of my invention and therefore I claim:

1. A suspension device to engage and clamp a conductor comprising clamping means to engage and clamp the conductor and provided with projecting means, a member mounted on and movable relatively to the clamping means and engaging the projecting means thereon to move the clamping means into engagement with the conductor, a supporting member provided with internal means rotatably mounted to engage external means on the clamping means and means to engage a support.

2. A suspension device to engage and clamp a conductor comprising clamping means to engage and clamp the conductor, a member rotatably mounted on and movable relatively to the clamping means to move the clamping means into engagement with the conductor, a supporting member rotatably mounted exterior of the clamping means to retain the clamping means in a clamping position, and means to secure the device to a hanger.

3. A supporting device to engage and clamp a conductor comprising a supporting member, means to engage a hanger, clamping means rotatably mounted within the supporting member and held in clamping position thereby and arranged to clamp a conductor, and a member mounted on the supporting member and movable longitudinally thereof to engage the clamping means and move them into clamping engagement with the conductor.

4. A suspending device to engage and clamp a conductor comprising a supporting member, a pair of clamping jaws and a collar, the collar arranged to engage and move the jaws into engagement with the conductor and to move longitudinally with respect to the jaws and supporting member and to engage the supporting member to rotate in unison therewith and relatively to the jaws, internal means on the supporting member engaging external means on the jaws for locking the jaws in rotatable relation to the

- support member to maintain the jaws in a clamping position, and means to secure the device to a hanger.
5. A supporting device to engage and clamp a conductor comprising a supporting member, means to engage a hanger, clamping means rotatably mounted within the supporting member and held in clamping position thereby and arranged to clamp a conductor, and an operating member mounted on the supporting member and movable longitudinally thereof to engage the clamping means and move them into clamping engagement with the conductor and means 15 on the supporting member engaging means on the operating member to prevent the removal of the parts of the device and limit the longitudinal movement of the operating member in one direction only.
- 20 6. A suspending device to engage and clamp a wire comprising a supporting member provided with means for engaging a hanger or support and provided with internal means to engage a wire clamping means, wire clamping means provided with means for engaging and clamping a wire and also having means to interlock with the internal means on the supporting member to prevent separation of the supporting member and 25 the clamping means but permitting relative rotation, and a member adapted to engage and move the clamping means into clamping engagement with the wire and moving relatively to the supporting member.
- 30 7. A suspension device to engage and clamp a conductor comprising a suspension member, a pair of jaws and a collar member, the suspension member adapted to support and retain the jaws together and provided with an internal recess and shoulder and the jaws provided with an external recess and flange adapted to engage the internal flange and recess respectively of the suspension member to permit of free relative 35 rotation, the collar adapted to move relatively to the jaws and suspension member whereby the jaws are made to grip the wire, the suspension member also having means for attachment to a hanger or support.
- 40 8. A suspension device to engage and clamp a conductor comprising a pair of clamping jaws, a supporting member provided with an external recess and an opening to the recess to permit assembling the 45 clamping jaws and the supporting member, means on the jaws to engage the recess and interlock the parts together but to permit relative rotation, means on the support member to engage a hanger or support, a
- collar arranged to rotate with the support member and to be interposed between the jaws and the hanger and movable longitudinally to the supporting member to move the jaws into engagement with the conductor when the collar engages the hanger and 55 is rotated.
5. A suspension device to engage and clamp a conductor comprising a supporting member provided with means to secure the device to a hanger, two jaws, the jaws and supporting member provided with coacting means whereby the jaws are fulcrumed within the suspension member and mounted to rotate relatively to each other, means projecting from each jaw to be engaged to move the jaws into clamping engagement with a conductor and means to engage the projecting means to move the jaws.
- 10 6. A suspending device to engage and clamp a conductor comprising a supporting member provided with means to secure the device to a hanger, two jaws, the jaws and supporting member provided with coacting means whereby the jaws are fulcrumed to 60 the supporting member, means projecting from each jaw to one side of the vertical axis of the device and below the point of fulcrum and means adapted to engage the projecting means and force the jaws into 65 clamping engagement with the conductor.
- 15 7. A suspending device to engage and clamp a conductor comprising a supporting member, means to engage a hanger, clamping means supported from within the supporting member and held in clamping position thereby and arranged to clamp a conductor, an operating member mounted on the supporting member and movable longitudinally thereof to engage the clamping 70 means and move them into clamping engagement with the conductor.
- 20 8. A suspending device to engage and clamp a conductor comprising a supporting member provided with means to secure the device to a hanger, two jaws, the jaws and supporting member provided with coacting means whereby the jaws are fulcrumed to 75 the supporting member, means projecting from each jaw to one side of the vertical axis of the device and below the point of fulcrum and means adapted to engage the projecting means and force the jaws into 80 clamping engagement with the conductor.
- 25 9. A suspension device to engage and clamp a conductor comprising a supporting member provided with means to secure the device to a hanger, two jaws, the jaws and supporting member provided with coacting means whereby the jaws are fulcrumed to 85 the supporting member and mounted to rotate relatively to each other, means projecting from each jaw to be engaged to move the jaws into clamping engagement with a conductor and means to engage the projecting means to move the jaws.
- 30 10. A suspending device to engage and clamp a conductor comprising a supporting member provided with means to secure the device to a hanger, two jaws, the jaws and supporting member provided with coacting means whereby the jaws are fulcrumed to 90 the supporting member, means projecting from each jaw to one side of the vertical axis of the device and below the point of fulcrum and means adapted to engage the projecting means and force the jaws into 95 clamping engagement with the conductor.
- 35 11. A suspending device to engage and clamp a conductor comprising a supporting member, means to engage a hanger, clamping means supported from within the supporting member and held in clamping position thereby and arranged to clamp a conductor, an operating member mounted on the supporting member and movable longitudinally thereof to engage the clamping 100 means and move them into clamping engagement with the conductor.
- 40 12. A supporting device to engage and clamp a conductor comprising a supporting member, means to engage a hanger, clamping means supported from within the supporting member and arranged to clamp a conductor, an operating member mounted on the supporting member and movable longitudinally thereof to engage the clamping 105 means and move them into clamping engagement with the conductor and means interposed between the operating and supporting members to limit the relative movement of these two members in one longitudinal direction.

In testimony whereof I affix my signature.
SAMUEL S. MATTHES.
